UNITED STATES PATENT OFFICE.

GEORGE TIBBETT, OF JACKSON, OHIO, ASSIGNOR OF ONE-HALF TO SIMON L. DAVID, OF JACKSON, OHIO.

JOURNAL-LUBRICATOR.

No. 821,208.

Specification of Letters Patent.

Patented May 22, 1906.

Application filed October 26, 1905. Serial No. 284,421.

To all whom it may concern:

Be it known that I, GEORGE TIBBETT, a citizen of Syria, residing at Jackson, in the county of Jackson and State of Ohio, have 5 invented certain new and useful Improvements in Journal-Lubricators, of which the following is a specification.

My invention relates to new and useful 10 improvements in lubricators for railway-car or other journals.

The object of the invention is to provide a 15 simple lubricator of superior construction in which the number of parts are reduced to a minimum and the cost of production greatly reduced.

Another object is to provide a device of the 20 character described that will be strong, durable, and efficient and one in which the several parts will not be liable to get out of working order.

With the above and other objects in view 25 the invention consists of the novel details of construction and operation, a preferable embodiment of which is described in the specification and illustrated in the accompanying drawings, wherein—

Figure 1 is a partial central longitudinal 30 sectional view of a journal-box embodying my invention and showing a portion of a car-axle in elevation. Fig. 2 is a vertical sectional view taken on the line $\alpha\alpha$ of Fig. 1 and looking in the direction of the arrow, and Fig. 3 is a perspective view of the mat and its supporting-basket.

In the drawings the numeral 1 designates 35 the car-axle journal, and 2 the ordinary journal-box.

In carrying out the invention an oil-containing receptacle or reservoir 3 is provided 40 and shaped so as to snugly fit within the lower portion of the journal-box. This receptacle may be formed from any suitable metal, either sheet or cast. Above the central portion and below the journal 1 the receptacle is formed with a horizontally-extending flange or shelf 4, preferably projecting 45 from the four sides of the receptacle, so as to provide a rectangular opening 5 in the center of the receptacle and directly beneath the journal. Within this receptacle an open-ended basket 6 is supported. The vertical sides 7 and the rounded bottom 8 of the basket are preferably formed from a single piece 50 of metal. The basket has a width and length

less than that of the opening 5, through 55 which it extends, so as to have free play therein. The sides 7 of the basket support at their upper ends a curved plate or rest 9, the cross-sectional contour of which conforms to the contour of the journal. This 60 plate 9 may be formed separately from the sides 7 of the basket or integral therewith, it being noted that the sides are curved outwardly and upwardly, so as to provide an additional support for the plate. On opposite 65 sides of the central portion the sides are provided with opposite vertical slots or openings 10. Rods or bars 11, extending transversely through the basket, project through the slots 10 some distance, so as to rest at 70 each end on the shelf or flange 4 at each side of the receptacle. Coiled springs 12 have their upper ends engaged about the center of the bars and are at their lower ends suitably secured to the bottom 8 of the basket. By 75 this provision the basket is yieldably supported, the springs being under a slight tension, so as to force the basket upward for the purpose hereinafter described.

On the upper side of the plate 9 I arrange 80 a mat 13, the body portion of which is formed of a suitable woven or knitted fabric. Through the body of the fabric strands of suitable material are passed. Several of these strands are connected together to form 85 wicks 14, which pass through apertures or openings 15, provided in the plate 9. The upper ends of the wicks or strands are threaded through the body of the mat and spread thereover, so as to provide a soft wearing- 90 surface of superior quality. The depending portions of the wicks which extend through the openings 15 are carried down through the basket 6, passing through transverse openings 16 in the bottom of the basket to 95 the receptacle and having their lower ends resting on the bottom thereof. The lower portion of the receptacle is filled with a suitable lubricant, which is drawn by capillary attraction up the wicks 14 to the mat 13. 100 The mat 13 absorbs the lubricant, so that the upper ends of the wicks provide a bed 17, which becomes thoroughly saturated with the lubricant and transmits the same to the journal 1, which rests on said bed. 105

By means of the springs 12 the basket 6 is forced upward, so that the bed 17 is held in close contact with the under surface of the

journal, and thus the same is maintained in a state of perfect lubrication. Any jar or vibration will of course be absorbed by the springs, which will also accommodate any lateral movement of the basket and act to hold the bed 17 of the mat in contact with the journal at all times, so that the perfection of the lubrication will not be affected.

It is to be noted that my lubricating device may be readily applied to the journal-box without in any way altering the construction thereof. Also by the provision of the receptacle or reservoir 3 for the lubricant the latter is prevented from coming in contact with the journal-box. The action of oil and other lubricants on cast metal, of which the journal-boxes are formed, is commonly known and by forming the receptacle of suitable metal the journal-box is entirely protected from the action of the oil or lubricant and its life prolonged.

Having now fully described my invention, what I claim, and desire to secure by Letters Patent, is—

1. The combination with a journal-box and an axle journaled therein, of a lubricant-receptacle fitting in the journal-box and provided with one or more inwardly-extending projections, a basket having a curved plate arranged in the receptacle, means having engagement with the projections of the receptacle for yieldably supporting the basket, and a mass or layer of fibrous material arranged on the curved plate of the basket in contact

with the axle and having portions depending 35 through the basket into the receptacle.

2. The combination with a journal-box and an axle journaled therein, of a basket arranged in the journal-box, springs confined within the basket, supports with which the 40 springs have connection passing through the basket, means fixed with relation to the basket for receiving the supports, and a mass or layer of fibrous material arranged on the basket in contact with the axle and having portions 45 depending through the basket into the receptacle.

3. The combination with a journal-box and an axle journaled therein, of a receptacle fitting in the journal-box and provided with 50 projections or extensions, a basket arranged between the projections, springs arranged in the basket and connected to the bottom thereof, supports extending through the basket having connection with the springs and 55 engaged at their ends with the projections, and a mass or layer of fibrous material arranged on the basket in contact with the axle and having wicks depending through the basket into the receptacle.

In testimony whereof I affix my signature in presence of two witnesses.

GEORGE X. TIBBETT.
